BORING APPARATUS

John W. French, Beverly, Mass., assignor to
 United Shoe Machinery Corporation, Paterson,
 N. J., a corporation of New Jersey

Application October 22, 1934, Serial No. 749,353

16 Claims. (Cl. 144—93)

This invention relates to apparatus for boring holes in work. A field in which it has special utility is in the drilling of shoe-heels for the insertion of screw-fastenings.

5. In the attaching of wood heels to shoes, a common practice is to apply an adhesive to the heel-seat of the shoe and the corresponding end of the heel, and secure these, while the adhesive is setting, by a screw which may be either temporary or permanent. In preparation for the insertion of the screw, a hole is drilled through the heel-seat of a lasted shoe into a heel clamped thereon, the drill passing through a guide-channel extending from the top of the last-cone to the heel-seat surface. The drilled hole in the heel should be somewhat deeper than is necessary to receive the screw, since the resistance offered to insertion when the point of the screw strikes the bottom of the hole may split the heel, strip the thread which the screw has cut in the wood, or cause the screw to be twisted off. On the other hand, if the hole is too deep the point of the drill may emerge through the tread-surface or peripheral wall of the heel. It is therefore important that the extent to which the drill enters shall be kept within rather narrow limits. This is difficult, because the work comes to the operator upon lasts having cones of different heights, and the surface of the cone can not be employed to determine when the drill begins its cut upon the heel-seat material hidden by the last or ends its progress into the heel. It is an object of my invention to provide for boring to a predetermined depth, however the surface entered may be concealed from the operator. To gain this end, I associate with a drill, or other unitary tool, means controlled by the engagement with the work of the entering portion of the tool for predetermining the passage of said tool into the work, or the extent of its effective operation, this being capable of variation. Therefore, regardless of the form or dimensions of the last or other object, by which portions of the work may be hidden, a definite entrance of the tool into said work is assured to the depth desired. As herein disclosed, a movable gage is provided, and this gage may be connected for movement with the spindle through which the tool is rotated by a clutch device, as by a detent engaging teeth upon the gage, this device being operable by a handle movable upon the spindle. When the advance of the tool has momentarily stopped by contact of its point with the work, continued movement of the handle which is being manipulated by the operator

causes the clutch device to couple the gage to the spindle, and the action of the tool upon the work continues to an extent determined by the setting of the gage.

The accompanying drawing illustrates one of many forms which my invention may assume, Fig. 1 being a side elevation of my improved boring apparatus;

Figs. 2 and 3, respectively, enlarged broken side elevations of the upper and lower portions of the apparatus; and

Fig. 4, a horizontal section on the line IV—IV of Fig. 3.

The features peculiar to my invention may be included in such an apparatus as that disclosed in Letters Patent of the United States No. 1,722,992, Bertrand, August 6, 1929. Upon a table 10 is carried a tread-plate 12 for a shoe S containing a last L and for a heel H, there being a back-stop 14 for the heel and a member 16 for clamping the shoe and heel together. At 18 appears a fragment of a frame-arm in which rotates a horizontal driving shaft 22. Gearing 24 transmits the rotation of the shaft 22 to the upper section 26 of a drill-spindle D, this section turning in a bearing 28 supported for universal movement upon the frame-arm 18. Connected to the spindle-section 26 is an extensible section 30 and to this is united a terminal section 32 by a universal joint 34. The section 32 has formed upon or secured to it a chuck 36 for a drill 38. A handle 40, in which the spindle-section 32 rotates freely, may be grasped and pressed down by the operator to cause the drill to cut.

As thus far described, the depth to which the drill may act, as a result of the movement of the spindle-sections 30 and 32 on the section 26, is dependent upon the necessarily inaccurate judgment of the operator, and this is made more uncertain by the changes in lasts, such as have already been mentioned. My invention furnishes automatically acting depth-terminating means in the following manner: From the bearing 28 and movable laterally with it a bracket-arm 42 depends. This has a vertical cylindrical extension 44 through which passes a gage-rod 46 splined to move longitudinally without rotation. The rod is held up in a normal position upon the supporting arm 42 by a spring 48 surrounding the extension and gage-rod, and abutting against the bracket 42 and against a nut and check-nut 50 threaded upon the upper extremity of the rod. The extent of upward movement of the rod under the influence of the spring is limited by a collar 52 which contacts with the under face of the

bracket. Downward movement of the rod 46 is variably determined by engagement of the lower nut 50 with the adjacent end of the extension 44. The rod extends substantially parallel to the spindle D, passing through a carrier and coupling member 54 which is held between a flange 56 and a nut 58 upon the upper extremity of the spindle-section 30. The spindle turns freely in the carrier which is itself held against rotation by the rod 46. Upon the carrier is pivoted a detent 60 arranged for engagement with a series of teeth 62 formed in the adjacent side of the gage-rod. To the outer wall of the carrier is secured a suspension-link 64 furnishing at its lower end a fulcrum for a lever 66. The inner end of the lever has upon it a yoke 68, the arms of which terminate at opposite sides of the center of the universal joint 34. Here, these arms are pivotally connected at 69 to arms 70, 70 which rise from the top of the handle 40. Between its ends, a link 72 joins the lever to the detent 60, the relation being such that downward movement of the link causes engagement of the detent with the teeth 62. The handle 40 is arranged to yield upon the spindle section 32 against a helical spring 74. This spring surrounds the spindle, contacting at its upper extremity with a shouder 76 at the end of a recess in which it is contained in the handle and at the bottom with an anti-friction bearing 78 interposed between it and the chuck 36. The expansive force of the spring urges the upper portion of the handle against an anti-friction bearing 80, the top of which rests against a collar 82 fast upon the spindle-section 32.

In using my improved apparatus, a lasted shoe S and its heel H are clamped as usual upon the supporting plate 12. The nuts 50 are so set upon the gage-rod 46 that the distance between the bottom of the lower nut and the top of the bracket extension 44 is equal to the distance which the drill 38 is to penetrate the work. Grasping the handle 40 and with the spindle D in rotation, the operator introduces the drill into the guide-channel of the last L and lowers it, the telescopic connection between the sections 30 and 26 permitting this. The spring 74 holds the handle in its normally raised position upon the section 32 until the point of the drill encounters the heel-seat of the shoe, which resists penetration. Then the handle yields, and, as it moves down, swings the lever 66 in an anti-clockwise direction, as viewed in the drawing. This, through the link 72, brings the detent 60 into engagement with the teeth 62 of the gage rod 46. There is thus furnished a clutch device which couples the rod and member 54, compelling them to move together. Now, said member can be moved down only until the nuts 50 strike the bracket-extension 44. Since the member 54 is held against movement longitudinally of the spindle-section 30, the entrance of the drill into the work is correspondingly limited. This is entirely independent of the character of the last, the drill being of sufficient length to bore the desired depth of hole in the heel for all heights of last-cones. The succeeding operations continue without attention on the part of the operator to the depth of drilling, unless a different length of screw is to be inserted. Then the operator has only to correspondingly vary the position of the nuts 50. Because the pivotal connection of the handle at 69 is at or near the center of the universal joint 34, the lever 66 is unaffected by the lateral swinging of the spindle-section 32 as it enters the 75 guide-holes of different lasts at varying angles.

The detent 60 is consequently not carried into clutching engagement with the teeth 62 until downward movement of the handle upon its spindle-section begins.

Having described the invention, what I claim as new and desire to secure by Letters Patent of the United States is:

1. In a boring apparatus, a boring tool, gaging means arranged to predetermine the depth to which the tool may enter the work, and means controlled by resistance of the tool to penetration of the work for rendering the gaging means effective.

2. In a boring apparatus, a movable drill-spindle, a gage member for the spindle, and means for coupling the gage member to the spindle under the control of the work.

3. In a boring apparatus, a movable drill-spindle, a movable gage member, means arranged to vary the extent of movement of the member, and means made effective upon change of movement of the spindle for coupling the member to said spindle for movement therewith.

4. In a boring apparatus, a movable drill-spindle, a handle movable upon the spindle, a gage member for the spindle, and means controlled by movement of the handle for coupling the gage member to the spindle.

5. In a boring apparatus, a rotatable spindle, a drill-holder carried by the spindle, a member yieldable upon the spindle toward the holder, a depth-gage movable longitudinally of the spindle, and means controlled by the member during its yield for coupling the gage to the spindle.

6. In a boring apparatus, a movable drill-spindle, a handle yieldable thereon, a gage movable adjacent to the spindle and at all times free from contact with the work, a clutch device for connecting the gage to the spindle, and connections to the handle for actuating the clutch device.

7. In a boring apparatus, a movable drill-spindle, a handle yieldable thereon, a gage movable adjacent to the spindle and provided with a series of teeth, a detent movable upon the spindle for engagement with the teeth, and a link connecting the handle to the detent.

8. In a boring apparatus, a drill-spindle rotatable and laterally movable during the application of the drill to the work, a bearing for the spindle, a member mounted upon the bearing to move along the spindle to a predetermined distance, and a coupling device for connecting the member to the spindle.

9. In a boring apparatus, a rotatable and laterally movable drill-spindle, a bracket arranged to move laterally with the spindle, a member mounted to move through the bracket longitudinally of the spindle, means arranged to vary the extent of movement of the member, and a coupling device for connecting the member to the spindle.

10. In a boring apparatus, a rotatable drill-spindle, a handle movable longitudinally of the spindle, a fulcrum member supported upon the spindle, a lever fulcrumed upon the member and connected to the handle, a gage member movable longitudinally of the spindle, a clutch device for joining the gage member to the spindle, and connections to the lever for actuating the clutch device.

11. In a boring apparatus, a rotatable drill-spindle, a handle movable longitudinally of the spindle, a fulcrum member supported upon the spindle, a fulcrum member being held by the gage member against rotation with the spindle,

a lever fulcrumed upon the member and connected to the handle, a gage member movable longitudinally of the spindle, a clutch device for joining the gage member to the spindle, and connections to the lever for actuating the clutch device.

12. In a boring apparatus, a rotatable drill-spindle formed in sections, a universal joint connecting the sections, a handle movable upon the 10 spindle, a gage member movable longitudinally of the spindle, a device for clutching the gage member to the spindle, a lever through which the clutch device may be actuated, and pivotal connections between the handle and the lever, 15 the pivotal axis lying at substantially the center of the universal joint.

13. In a boring apparatus, a rotatable drill-spindle, a handle movable longitudinally of the 20 spindle, a spring holding the handle normally raised upon the spindle, a toothed gage-rod movable longitudinally of the spindle, a member carried by the spindle, a detent pivoted upon the member, and a link communicating to the detent movement of the handle against the force of the 25 spring.

14. In a boring apparatus, a rotatable drill-spindle, a handle movable longitudinally of the spindle, a spring holding the handle normally

raised upon the spindle, a toothed gage-rod movable longitudinally of the spindle, a member held against movement upon the spindle longitudinally thereof and retained against turning by the gage-rod, a detent pivoted upon the member, and a link communicating to the detent movement of the handle against the force of the spring.

15. In a boring apparatus, a rotatable drill-spindle, a support associated therewith, a gage member movable upon the support, a spring interposed between the support and the gage member for holding said member in its normal position, connections to the spindle for moving the gage member, and variable means for limiting the extent of movement of the gage member 15 against the force of the spring.

16. In a boring apparatus, a rotatable drill-spindle, a support associated therewith and having an upward extension, a gage member movable upon the support and having a threaded portion 20 lying above the extension, a nut variable in position upon the threaded portion of the gage member and movable into contact with the extension, a spring interposed between the support and nut and surrounding the extension, and connections 25 to the spindle for moving the gage member.

JOHN W. FRENCH.
